UNITED STATES PATENT OFFICE

WALTER O. McDANIEL, OF MOORESVILLE, INDIANA, ASSIGNOR TO FALL CREEK MANUFACTURING COMPANY, OF MOORESVILLE, INDIANA, A CORPORATION OF INDIANA

DAVENPORT-CORNER CONSTRUCTION

Application filed May 5, 1928. Serial No. 275,406.

This invention relates in general to a frame construction for a combination davenport and bed and in particular to a corner construction of a movable back whereby the corner may be upholstered and extended laterally around a back supporting post to permit the corner to be moved as an integral part of the back without any division being made vertically therethrough above the davenport 10 arm over which the corner is extended.

The invention is described in reference to the accompanying drawings, in which—

Fig. 1 is a front elevation of one end of a davenport-bed embodying the invention;

Fig. 2, a side elevation of the davenport with the back in the raised position;

Fig. 3, a fragmentary rear elevation of the upper corner as shown in Fig. 1;

Fig. 4, a front elevation of the frame only 20 of the same upper corner;

Fig. 5, a side elevation of the frame shown in Fig. 4;

Fig. 6, a top plan view of the same portion of frame;

Fig. 7, a transverse horizontal section on the line 7—7 in Fig. 4;

Fig. 8, a side elevation of a hinge employed to carry the back;

Fig. 9, a rear elevation of the frame as 30 shown in Fig. 3 but showing a modified form of hinging the back; and

Fig. 10, a vertical section on the line 10—10 in Fig. 9, showing a still further modified form of swinging the back from its support.

Like characters of reference indicate like parts throughout the several views in the drawings.

Referring to Fig. 1, an end of a davenport is there shown with an upholstered arm 12. 40 The back 13 is movable so as to be moved outwardly and upwardly to permit a bed frame not shown) to be pulled out from under the back, the exact details of the mounting of the bed frame not entering into this 45 invention. Instead of cutting off the back on a vertical line extended upwardly from the inner side of the arm 12, I continue the back on out over the arm 12 to form the shoulder 14, which, while fitting snugly down over 50 the arm 12, is an integral part of the back

13 and may be moved therewith as indicated in Fig. 2, where the back 13 has been raised to its extreme outer and upper position and there supported by the hinged brace 15.

Referring now more particularly to Figs. 55 3, 4, 5 and 6, the davenport is built with the usual vertical rear corner post 16 from which the arm foundation board 17 extends horizontally forward. From near the top of the post 16 horizontally extends the brace board 60 18.

The back 13 has a frame piece 19 disposed vertically on edge with the upper edge cut to define the top line of the back. To the lower edge is attached the horizontally disposed frame piece 20 which extends on out around and past the post 16. The short plate 21 of the hinge, Fig. 8, is attached to the outer end of the frame piece 19 while the longer plate 22 is fastened on the inner side 70 at the top of the post 16.

The side piece 23 extends downwardly and 75 forwardly from the under side of the horizontal piece 20 spaced inwardly from the post 16, and the horizontal piece 24 extends horizontally from the lower end of the side piece 23 to form the lower edge of the back.

Cushion springs 25 are carried on the usual transverse bars 26.

A shoulder plate 27 is secured to the outer 80 end of the top piece 20, which piece is rounded on the end to curve around toward the front face of the plate 27. A block 28 of substantial thickness is secured to near the lower end of the plate 27 and is rounded 85 to extend forwardly and around and secured to the side piece 23 of the back, the plate 27 being thereby disposed to hang at a fixed angle behind the piece 23, and to be positioned normally in the same plane as 90 that of the upper portion of the post 16. The under side of the block 28 is arched to conform to the curvature of the top of the finished arm 12, as determined by the piece cut from the block 28 and attached to the arm 95 board 17.

It is to be seen, therefore, that when the back 13 is pulled outwardly, it pivots in the hinge at the top of the post 16, and the plate 27 is swung accordingly from out past the 100

post 16 and is returned when the back 13 is dropped back. The covering of the back is carried around over suitable padding over the block 28 at the bottom and around the edge of the plate 27 to give the desired shape to the shoulder.

The frame construction so described not only permits the carrying of a projected shoulder integrally as a part of the back, but also aids considerably in bracing the back frame to hold it square as it is swung in and out. While the back 13 has been described as being pivotally swung from near its top edge and the top of the post 16 to permit the back covering 30 to be secured to the piece 19 the back may be hinged to the brace board 18, Fig. 9, or where it is not desirable to hinge the back, it may be supported on the swinging bars 31 and 32, Fig. 10.

20 In either of these modified methods of carrying the back, the plate 27 is brought back to lie along and extend laterally from the post 16, the post 16 always being concealed by the shoulder 14 formed thereover.

25 While I have described my invention in the form it is now best known to me, it is obvious that structural changes may be made without departing from the spirit of the invention, and I therefore do not desire to be limited to the precise form as shown, nor any more than may be necessitated by the following claims.

I claim:

1. In a davenport, a movable back, a fixed back supporting post, said back being normally positioned to one side of the post, and a shoulder comprising means carried by and extended from the end of the back adapted to be normally around said post and extended laterally therefrom and a block attached at one end to the back and at its other end to the lower end of the shoulder means.

40 2. In a davenport, a fixed back post, an arm extended from the post, a back having means by which it is swingingly supported in relation to the post to swing past the inner side of the arm, a shoulder plate, members securing the shoulder plate to the back comprising a top frame-piece and a lower block, said plate being positioned by the members to pass on the outer side of the post in immediate proximity over said arm and the block being recessed to conform to the top finish of the arm.

45 3. In a davenport, a movable back having a top horizontal frame piece, a lower horizontal frame piece, and a vertical side piece interconnecting said two frame pieces, a fixed back frame, an arm extending from said back frame, said movable back being swingingly supported in relation to said fixed back frame whereby the lower portion of the movable back swings past the inner side of the arm, a shoulder plate extended from the said back side piece to swing with the movable back

and to extend laterally from the end of the fixed back frame over said arm and means connecting the side piece with the plate to swing the plate with the back to a normal position outside of the frame over the arm.

4. In a davenport, a movable back having a top piece, a bottom piece and a vertical side piece interconnecting said top and bottom pieces, a fixed back frame, an arm extending from said back frame, said movable back being swingingly supported in relation to the back frame whereby the lower portion of the movable back swings past the inner side of the arm, a shoulder plate, said top piece being extended and attached to the upper end of the plate, a block secured to the said side piece and extended outwardly to be secured by its outer portion to the lower end of the plate, said plate being thereby positioned from the side of said movable back to swing with the movable back and to hang normally at the outer side of the back frame over said arm.

50 In testimony whereof I affix my signature.

WALTER O. McDANIEL.
